UNITED STATES PATENT OFFICE

161,367

TOY VEHICLE

Glenn Periman, Los Angeles, Calif.

Application March 18, 1948, Serial No. 145,206

Term of patent 3½ years

(Cl. D34—15)

To all whom it may concern:

Be it known that I, Glenn Periman, a citizen of the United States and a resident of Los Angeles, county of Los Angeles, State of California, have invented a new, original, and ornamental Design for a Toy Vehicle, of which the following is a specification, reference being had to the accompanying drawing, forming part thereof.

Referring to the drawing:

Figure 1 is a side elevation of a toy vehicle, showing my new design;

Figure 2 is a top plan view of the vehicle;

Figure 3 is a front elevation of the vehicle; and

Figure 4 is a rear elevation thereof.

I claim:

The ornamental design for a toy vehicle, as shown.

GLENN PERIMAN.
